DIAPHRAGM VALVE

Walter Kreis, Neuhausen, and Paul Troesch, Schaffhausen, Switzerland, assignors to Georg Fischer Aktiengesellschaft, Schaffhausen, Switzerland, a corporation of Switzerland

Filed June 24, 1969, Ser. No. 17,857

Claims priority, application Switzerland Feb. 3, 1969

Term of patent 14 years

Int. Cl. D23—01

U.S. Cl. D23—19

FIG. 1

FIG. 3

FIG. 2

FIG. 4

FIG. 5

FIG. 1 is a perspective view of a diaphragm valve embodying our new design;

FIG. 2 is a front view thereof, the opposite front portion thereof being identical to that shown;

FIG. 3 is a side view thereof, as viewed from the left of FIG. 2, the opposite side being identical to the side shown;

FIG. 4 is a top plan view thereof; and

FIG. 5 is a bottom plan view thereof.

We claim:

The ornamental design for a diaphragm valve, as shown and described.
